UNITED STATES PATENT OFFICE

2,487,534

MANUAL RESET SEQUENTIAL TRIP SWITCH
MECHANISM

John A. Favre, Drexel Hill, Pa., assignor to General Electric Company, a corporation of New York

Application July 8, 1948, Serial No. 37,636

10 Claims. (Cl. 200—116)

1
The invention relates to manual reset sequential trip switch mechanisms, particularly of the type having thermal overload sequential tripping means and a common reset member controlling a pair of switches.

One of the objects is to provide an improved mechanism of the above type for enabling a manually operable trip-free thermal overload circuit breaker such, for example, as disclosed in my Patent 2,435,432 to pre-trip a warning signal switch when a partial overload approaches the value at which the circuit breaker is calibrated to trip as well as to manually reset the signal switch with the circuit breaker either tripped or untripped.

Another object is to provide an improved form of dual-switch mechanism having a tripping member movable to effect tripping of one or both of the switches dependent upon the extent of movement of the trip member and having a manual control member movable selectively in opposite directions for resetting the first tripped switch separately or jointly with the second switch in case it also has been tripped.

Another object is to provide a manually reset thermal overload circuit breaker with an improved form of warning signal switch mechanism that can be tripped before the circuit breaker is tripped and can be reset either by moving the circuit breaker manual reset member in the direction required to reset the circuit breaker or by moving the manual operating member in the opposite direction when the circuit breaker is closed.

Another object is to provide for adjustably calibrating the amount of overload required to pre-trip the warning signal switch without varying or interfering with the calibration of the overload tripping value of the circuit breaker.

Further objects and advantages of the invention will appear in the following description of the accompanying drawings showing a preferred form of the invention and its scope is pointed out in the appended claims.

In the drawing Fig. 1 is a side view of a manual trip-free thermal overload circuit breaker provided with the improved pre-trip signal switch and having some of the parts broken away in order more clearly to show the details of construction. Fig. 2 is a partial top view and Fig. 3 is an end view of the switch mechanism shown in Fig. 1. Fig. 4 is a partial side view of the switch mechanism shown in Fig. 1 indicating the relative positions of the parts when the signal switch is tripped before the circuit breaker is

tripped while Fig. 5 shows the relative position of the parts when the signal switch is separately reset with the circuit breaker still untripped. Figure 6 shows the signal switch connected to a signal lamp.

2
As shown in Fig. 1 the circuit breaker manual reset and trip-free operating mechanism is of the same construction as described and claimed in my Patent 2,435,432. In this construction a pair of movable circuit breaker contacts 10 are slidably carried in alignment in a movable frame 11 formed of molded insulating material and having a pivot mounting pin 12 anchored in the molded base 13. The current is conducted to each contact 10 by a separate flexible connector 14. The cooperating stationary circuit breaker contacts 15 are secured to the base 13 by rivets 16 which also serve to mount in conducting relation therewith one end of the thermal current responsive bimetal operating elements 17 that carry the adjustable operating finger 18 at the free end thereof. Upon heating of the thermal element 17 by the current through the contacts 10—15, the finger 18 is carried into operating engagement with the projection 19 of the circuit breaker trip element 20 that is pivotally mounted on the molded base 13 by means of the pivot pin 21. The spring 22 serves to bias the trip member 20 into position in which the adjustable trip plate 23 engages the latch 24 of the overcenter spring trip-free operating mechanism indicated generally by the reference character 25. This mechanism is provided with a manual operating member 28 of U-shape and having its two spaced-apart tapering legs 29 pivotally mounted in V-shaped pockets 30 formed in the molded base 13. The overcenter spring 31 has one end connected to the manual operating member 28 as shown and the other end connected to the central pivot 32 of the toggle 33 having one end thereof connected to the molded circuit breaker contact carrying frame 11 by pin 34 and the other end thereof connected to a collapsible lever 35 by means of the pin 36. The collapsible lever 35 is pivotally mounted on the base 13 by means of the pivot pin 38 and is held rigidly in place by means of the compound lever latch mechanism 40 that is maintained in a rigid condition when the latch 24 engages with the latch plate 23.
Thus as described more in detail in my prior patent, as long as the circuit breaker latch 24 is not tripped by operation of the thermal current responsive element 17, the manual control member 28 may be moved to the circuit closing position in which it is shown in Fig. 1 so as to carry

spring 31 over center to the left of pin 36 and thereby straighten toggle 33 to engage the movable circuit breaker contact 10 with the stationary contact 15. Likewise when manual control member 28 is moved to the circuit opening position, spring 31 is carried to the right-hand side of pin 36 and hence becomes effective to collapse the toggle 33 and thereby effect disengagement of the movable circuit breaker contact 10 from the stationary contact 15.

In case an overload current passes through the circuit breaker contacts 10-15 and heats the bimetal element 17 sufficiently to raise finger 18 and thus tilt trip member 20 about pivot 21 to release the adjustable calibrating plate 23 from the latch 24, then the collapsible latch mechanism 40 becomes effective to free the reset lever 35 for movement under the bias of spring 31 about its pivot 38 to carry the toggle pivot 36 to the left of spring 31 and thereby permit the spring to collapse the toggle 33 and disengage the movable circuit breaker contact 10 from the stationary contact 15. When the bimetal element 17 has cooled sufficiently to permit the trip member 20 to return to its normal latching position as shown in Fig. 1, then the circuit breaker latch 24 may be reset by moving manual control member 28 to the right towards its circuit opening position. This will cause member 28 to engage with the upper end 35' of reset member 35 and thereby return the reset member 35 to the position in which it is shown in Fig. 1 and at the same time operate the compound latch mechanism 40 to cause latch 24 to reengage with the calibration plate 23 of the trip member 20. Thereupon the overcenter spring 31 and toggle 33 again become effective to close the circuit breaker when the manual control member 28 is returned to the circuit closing position in which it is shown in Fig. 1.

In accordance with the present invention, the pre-trip signal switch indicated generally by the reference character 45 is combined with the thermal overload circuit breaker mechanism so that the signal switch 45 is tripped by operation of the tripping member 20 when the overload approaches the value to which the circuit breaker is calibrated to trip and can be reset by operation of the manual control member 28 in opposite directions with the circuit breaker tripped and untripped. In the improved form shown the signal switch 45 is provided with a U-shaped frame 46 having the oppositely bent ends 46' of the legs thereof secured to the circuit breaker molded base 13 by means of hollow rivets 47 as shown more clearly in Figs. 2 and 3. The frame 46 carries a stationary contact member 48 suitably secured thereto by the terminal bolt 49 and insulated therefrom by the grommet 50 and strip 50' of suitable insulating material. The cooperating movable signal switch member or bar 51 is welded to and hence carried by a sliding actuating member 52 that extends through the elongated adjusting slot 53 formed in the top part of the frame 46 and also through a free running guide slot in the cross member 54 that extends between the legs of the frame 46. A biasing spring 55 is interconnected at an angle between the signal actuating member 52 and the cross member 54 so as to bias the lower end of the sliding member 52 into accurate latching engagement with the calibrating plate 23 of the circuit breaker trip member 20 to be released thereby before the circuit breaker latch 24 is released when the trip member 20 is moved by the thermal element 17. In order to adjust the value of partial overload

required to trip the actuating member 52, the upper end thereof is arranged to slide in the rectangular notch 58 formed in an adjusting plate 59 that is adjustably secured to the top 46' of the frame 46 by means of the holding-down screw 60. Thus upon loosening screw 60 and suitably adjusting plate 59, the lower end of the sliding actuating member 52 may be moved laterally more or less adjacent to the edge of the trip plate 23 so as to vary the amount of movement of the trip member 20 required to trip the signal actuating member 52 before the circuit breaker is tripped. Upon the resulting engagement of the movable signal switch member 51 with the stationary switch member 48 as shown in Fig. 4 a circuit to a signal lamp or other suitable warning device can be closed with the circuit extending through the frame 46 of the signal switch which may be grounded as shown in Fig. 6.

In order to reset the actuating member 52 into engagement with the adjustable trip calibration plate 36 of the circuit breaker trip member 20 with the circuit breaker both tripped and untripped, a reversably removable reset in the form of a double opposing cam member 62 is provided and connected to be operated by movement of the manual control member 28 in opposite directions. The opposing cam member 62 is carried at the end of a connecting link 63 that slides in a slot 64 so as to engage either side of the cam member 62 with the contact bar 51 and thereby raise the bar 51 to reengage the lower end of the sliding actuating member 52 with the trip plate 23. The connecting link 63 is provided with an arcuate lost-motion slot 65 for receiving a pin 66 that is carried by the manual control member 28. This provides a lost-motion operating connection between the manual control member 28 and the opposing cam member 62 that can be taken up in either direction. The connecting link 63 also is provided with a bent ear 68 having an opening therein for receiving the hairpin loop end 69 of the tightly-coiled stiff spring 70 having the other end thereof secured to the cross member 54. Thus the link 63 in conjunction with the stiff spring 70 forms a resilient stop for engaging the pin 66 that is carried by the manual control member 28 against the left-hand end of the lost-motion slot 65 so as to limit the motion of the manual control member 28 to the circuit closing position in which it is shown in Fig. 1. However, when the stiff spring 70 of the resilient stop is flexed by movement of the manual control member 28 to the left to a position indicated by the dot-dash lines, then the connecting link 63 will since the lost motion is taken up move the opposing cam member 62 so as to engage the right-hand side thereof with the movable contact bar 51 as indicated in Fig. 5 and thereby reset the sliding actuating member 52 into engagement with the trip plate 23 with the circuit breaker in the untripped position as shown in Fig. 1.

In case the circuit breaker latch 24 has been tripped after the signal actuating member 52 has tripped then the manual control member or handle 28 must be moved in the direction of the circuit opening position in which it is shown in Fig. 4 in order to reset the latch 24. When the latch 24 is released, and the breaker opens, the carrier 35 rotates counterclockwise a limited distance. The spring bias on the handle 28 is thus shifted causing the latter to move in a clockwise or opening direction until it strikes the projection 35' about midway and stops, thus indicating the breaker has tripped. To reset the

breaker, the handle 28 must be pushed manually from this midpoint to the full open position, thus returning 35 and 25 to the positions shown in Fig. 1. At the same time the pin 66 carried by handle 28 engages the right-hand end of the slot 65 to take up the lost motion and thus moves the link 63 to carry the left-hand side of the opposing cam member 62 into engagement with the movable contact bar 51 and thereby raise the sliding actuating member 52 to reset the lower end thereof into engagement with the trip plate 23. In this way the warning signal switch is reset jointly with the resetting of the circuit breaker latch 24.

What I claim as new and desire to secure by Letters Patent of the United States is:

1. In a sequential trip switch mechanism, a movable trip member, means for moving said member, a pair of switches provided with separate latch elements biased into latching engagement with the trip member to be sequentially released thereby to trip one or both of said switches dependent upon the extent of movement of the trip member in one direction, and a reset member having connections including a reversely movable double cam for jointly resetting said latching elements upon movement of the reset member in one direction and separately resetting the latch element of said one switch upon movement of the reset member in the opposite direction. 15
2. In a sequential trip switch mechanism, a movable trip member, means for moving said member, a pair of switches provided with separate latch elements biased into latching engagement with the trip member to be sequentially released thereby to trip one or both of said switches dependent upon the extent of movement of the trip member in one direction, separate means for adjusting the extent of movement of said trip member required to trip each of said latch elements, and a reset member having connections including a reversely movable double cam for jointly resetting said latching elements upon movement of the reset member in one direction and separately resetting the latch element of said one switch upon movement of the reset member in the opposite direction. 20
3. In a sequential trip switch mechanism, a movable trip member, thermal overload means for moving said member to a variable extent in one direction, a pair of switches provided with separate latch elements biased into latching engagement with the trip member to be sequentially released thereby to trip one or both of said switches dependent upon the extent of movement of the trip member in said one direction, and a manual reset member movable in opposite directions and having a lost motion connection for resetting the latch element of said one switch upon movement of the reset member in each direction and separate connections for resetting the latch element of the other of said switches upon movement of the reset member in one direction. 25
4. In a condition responsive sequential trip switch mechanism, a reversely movable trip member biased to move in one direction, condition responsive means for moving said member in the reverse direction upon corresponding variation of a condition, a pair of switches provided with separate latch elements biased into latching engagement with the trip member to be sequentially released thereby to trip one or both of said switches dependent upon the extent of movement of the trip member in the reverse direction, and 30
5. a manual reset member having a lost motion connection including an opposing cam member for resetting the latch element of said one switch upon movement of the reset member in each direction and separate connections for resetting the latch element of the other of said switches upon movement of the reset member in one direction. 35
6. In a circuit breaker mechanism having a thermal overload trip member and a reset member movable from the reset position to close the breaker, a resilient stop limiting the movement of the reset member to the breaker closing position, a partial overload signal switch having a latch biased into latching engagement with said trip member to be pre-tripped thereby before the breaker is tripped, and means for resetting said latch while the breaker is closed including a reset member having a lost-motion connection with said control member taken up upon movement of the control member to flex said stop. 40
7. In a circuit breaker mechanism having a thermal overload trip member and a manual operating member movable between breaker opening and closing positions, a resilient stop limiting the movement of the control member to the breaker closing position, a partial overload signal switch having a latch biased into latching engagement with said trip member to be pre-tripped thereby before the breaker is tripped, and means for resetting said latch while the breaker is closed or opened including a reversely movable reset member having a lost-motion connection with said operating member taken up both upon movement of the member to flex said stop and to the breaker opening position. 45
8. In a circuit breaker mechanism having a thermal overload trip member, a latch released thereby to trip the breaker, a manual operating member having breaker opening and closing positions and provided with means for resetting said latch in the breaker opening position, a resilient stop limiting the movement of the operating member to the breaker closing position, a partial overload signal switch having a latch biased into latching engagement with said trip member to be pre-tripped thereby before the circuit breaker latch is tripped, and means for resetting said signal switch latch while the breaker is closed or opened including a reversely movable opposing cam reset member having a lost-motion connection with said operating member taken up both upon movement of the member to flex said stop and to the breaker opening position. 50
9. In a circuit breaker having a combined manual and automatic operating mechanism provided with a manual control member movable in one direction for opening and in the opposite direction for closing the breaker and with thermal overload means having a tripping member movable thereby to the circuit breaker-tripping position, an auxiliary actuating member having means for biasing said member into engagement with the circuit breaker tripping member to be released thereby before the tripping member reaches the circuit breaker tripping position, a signal device operated by said biased actuating member upon release thereof, and lost motion reset connections extending between said actuating member and said manual control member for resetting the actuating member into engagement with the tripping member upon movement of the manual control member in said one direction with the breaker open and in the opposite direction with the breaker closed. 55
10. In a circuit breaker having a combined manual and automatic operating mechanism provided with a manual control member movable in one direction for opening and in the opposite direction for closing the breaker and with thermal overload means having a tripping member movable thereby to the circuit breaker-tripping position, an auxiliary actuating member having means for biasing said member into engagement with the circuit breaker tripping member to be released thereby before the tripping member reaches the circuit breaker tripping position, a signal device operated by said biased actuating member upon release thereof, and lost motion reset connections extending between said actuating member and said manual control member for resetting the actuating member into engagement with the tripping member upon movement of the manual control member in said one direction with the breaker open and in the opposite direction with the breaker closed. 60
11. In a circuit breaker having a combined manual and automatic operating mechanism provided with a manual control member movable in one direction for opening and in the opposite direction for closing the breaker and with thermal overload means having a tripping member movable thereby to the circuit breaker-tripping position, an auxiliary actuating member having means for biasing said member into engagement with the circuit breaker tripping member to be released thereby before the tripping member reaches the circuit breaker tripping position, a signal device operated by said biased actuating member upon release thereof, and lost motion reset connections extending between said actuating member and said manual control member for resetting the actuating member into engagement with the tripping member upon movement of the manual control member in said one direction with the breaker open and in the opposite direction with the breaker closed. 65
12. In a circuit breaker having a combined manual and automatic operating mechanism provided with a manual control member movable in one direction for opening and in the opposite direction for closing the breaker and with thermal overload means having a tripping member movable thereby to the circuit breaker-tripping position, an auxiliary actuating member having means for biasing said member into engagement with the circuit breaker tripping member to be released thereby before the tripping member reaches the circuit breaker tripping position, a signal device operated by said biased actuating member upon release thereof, and lost motion reset connections extending between said actuating member and said manual control member for resetting the actuating member into engagement with the tripping member upon movement of the manual control member in said one direction with the breaker open and in the opposite direction with the breaker closed. 70
13. In a circuit breaker having a combined manual and automatic operating mechanism provided with a manual control member movable in one direction for opening and in the opposite direction for closing the breaker and with thermal overload means having a tripping member movable thereby to the circuit breaker-tripping position, an auxiliary actuating member having means for biasing said member into engagement with the circuit breaker tripping member to be released thereby before the tripping member reaches the circuit breaker tripping position, a signal device operated by said biased actuating member upon release thereof, and lost motion reset connections extending between said actuating member and said manual control member for resetting the actuating member into engagement with the tripping member upon movement of the manual control member in said one direction with the breaker open and in the opposite direction with the breaker closed. 75

7
9. In a circuit breaker having an operating mechanism provided with a pivotally mounted control member manually movable in opposite directions for respectively opening and closing the breaker and thermal current responsive means having a circuit breaker pivoted tripping member movable thereby to the circuit breaker tripping position, a biased actuating member slidably mounted for engagement with the pivoted tripping member to be released thereby before said member reaches the circuit breaker tripping position, an auxiliary switch operated by said biased actuating member upon release thereof, a link having a lost motion connection with said pivotally mounted manual control member and an opposing cam member operated by said link for resetting the slidably mounted actuating member into engagement with the pivoted tripping member upon movement of the manual control pivoted member in opposite directions with the breaker respectively opened and closed.

10. In a sequential trip switch mechanism, a movable trip member having thermal current responsive operating means, a pair of switches provided with separate latch elements biased into latching engagement with the trip member to be sequentially released thereby to trip one or both of said switches dependent upon the extent of movement of the trip member in one direction, one of said switches having a trip-free

15 overcenter spring operating mechanism provided with a manual-operating member reversely movable between two positions for opening and closing said one switch when the latch element thereof is in latching engagement with the trip member and provided with means for resetting said latch element upon movement of said operating member to the circuit opening position thereof, a resilient stop limiting the movement 20 of the manual operating member to the switch closing position, and said manual operating member having lost motion connections including an opposing cam member for resetting the latch element of the other of said switches upon movement of said operating member to the switch opening position thereof and separately resetting said latch element upon movement of said operating member to flex said resilient stop.
